United States Patent Office

Des. 181,050

Patented Sept. 24, 1957

181,050

NEWSPAPER RACK OR THE LIKE

Carl M. Harden, Whittier, Calif.

Application January 16, 1956, Serial No. 39,773

Term of patent 14 years

(Cl. D33—2)

FIG. 2.

FIG. 1.

FIG. 3.

Figure 1 is a side elevational view of a newspaper rack or the like showing my new design;

Figure 2 is an end elevational view thereof; and

Figure 3 is a top plan view of the rack.

I claim:

The ornamental design for a newspaper rack or the like, substantially as shown.
